UNITED STATES PATENT OFFICE.

SOLOMON RITTER HIPPLE, OF WILLIAMSPORT, PENNSYLVANIA, AND WALTER LEWIS CONWELL, OF MONTCLAIR, NEW JERSEY.

CONTACT SWITCH-BOX.

1,105,907.

Specification of Letters Patent.

Patented Aug. 4, 1914.

Application filed June 17, 1912. Serial No. 704,152.

To all whom it may concern:

Be it known that we, SOLOMON RITTER HIPPLE and WALTER LEWIS CONWELL, citizens of the United States, residing at Williamsport, in the county of Lycoming and State of Pennsylvania, and at Montclair, in the county of Essex and State of New Jersey, respectively, have invented certain new and useful Improvements in Contact Switch-Boxes; and we do hereby declare the following to be a full, clear, and exact description of the invention, such as will enable others skilled in the art to which it appertains to make and use the same.

This invention relates to electric railways of that type in which switch boxes are located at intervals along the road bed and successively rendered alive from a feed wire by the movement of the switches under the influence of magnets on the motor car for the purpose of supplying current to the propelling motors of the cars as they pass over the track.

One important object of the present invention is to sufficiently increase the magnetic torque or pull upon the movable contact member of the switch to insure the continuous engagement of said movable contact member with the fixed contact member throughout the interval of time during which the collector shoe on the car is in contact with the switch box, thereby avoiding arcing or sticking and rendering certain the uninterrupted flow of the electric current to the driving motor on the car. By employing this invention a pressure of from nineteen to twenty pounds may be secured between the contact members of the switch whereas only about five pounds pressure was obtainable with prior devices of this kind. Experiment has shown that it is necessary for the proper operation of this type of electric railway system to have substantially the pressure produced by the present construction, the much lower pressure which other devices are capable of producing having proved insufficient and impracticable.

Another object is to provide a simplified and reliable magnetically operated contact box in which the contacts of the switch are

brought into engagement only by the magnetic lines of force passing from the magnets on the car to and through the box so that only those boxes will be energized that are immediately under the car, the other boxes being dead.

The invention also has for its object the provision of a switch box in which access to the working parts and the making of repairs when necessary will be facilitated and a further object is to provide a switch box in which dissipation of the current and the formation of short circuits will be prevented.

A further object of the invention is to improve the connection between the feed wire or cable and the fixed contact of the switch as well as to provide simple and efficient means to secure the cable in position relative to the box and to aid in holding the box in position on the railway tie or other support.

With these and other incidental objects, which will appear as the description proceeds, in view, the invention consists in certain novel features which will be first fully described hereinafter and then set forth with particularity in the claims appended hereto.

In the accompanying drawings, which illustrate one embodiment of the invention, Figure 1 is a central longitudinal section of the contact switch box. Fig. 2 is a plan view thereof. Fig. 3 is an elevation of the cable end of the switch box. Fig. 4 is a vertical section on line 4—4, Fig. 1. Figs. 5 and 6 are vertical sections on line 5—6, Fig. 1, looking respectively to the right and left thereof. Fig. 7 is a perspective view on a reduced scale of the housing or casing of the switch box. Fig. 8 is a detail sectional view of a modified form of cover. Fig. 9 is a detail perspective view of the movable contact.

The body or housing 1 of the switch box is preferably molded of concrete or similar material and presents an open-top chamber 2, the said body having flanges or base extensions 3, 4, at its opposite ends that are reinforced by metal or other bars 5 embedded therein. The body is placed on a cross

tie of the roadbed and has one end fastened thereto by bolts 6 passed through metal bushings 7 in the base extension 3 while the other base extension, 4, is in the form of a trough-like seat 8 through which the feed wire or supply conductor, in the present instance a cable 9 housed in a pipe 10, extends. U-shaped clips 11 straddle the conductor adjacent the ends of the base extension 4 and depend below the body of the box to overlap the tie or other support on which the box is mounted. The ends of the clips are secured to the tie or other support by any convenient fastening devices and they therefore hold the feed wire in proper relation to the housing and also secure the housing to its support so that the use of bolts or other devices which would tend to interfere with the placing of the feed wire is rendered unnecessary.

Within the housing is a plate or block 12 of insulation fitted to the end wall of the chamber 2 and having secured thereto a fixed contact 13. This contact comprises an angular bracket 14 which has its base 15 bearing on the plate 12 and fitted between vertical ribs 16 thereon, the upper member of the bracket being formed with a stiffening rib 17. Passing through the wall of the housing, the plate 12 and the base 15 of the bracket 14, is a bolt 18 which is insulated from the housing by a bushing 19 of insulation. The head 20 of the bolt is partially set into the head 21 of the bushing and the inner end of the bolt is threaded to receive a nut 22 which holds the parts in place, there being a spring 23 and a washer 24 interposed between the nut and base of the bracket so that the parts cannot work loose under the vibration of the roadbed. The contacting surfaces of the base and the washer may be serrated, as shown at 25, to prevent loosening and the bracket is preferably slotted, as shown at 26, to facilitate accurate adjustment. On the bracket 14 is a carbon block or equivalent member 27 providing a surface against which the movable contact bears when the circuit is closed through the switch box. The carbon block 27 is secured to the bracket by bolts 28 inserted through the said block and the bracket and equipped with nuts 29 as shown. To prevent the splitting or cutting of the block around the head of the bolt, we provide clamping plates 30 which bear against the block and receive the impact of the head of the bolt as shown most clearly in Fig. 6. A piece of copper netting or similar material 31 is fitted between the carbon block and the bracket, providing an air space between them which serves to cushion said carbon block and prevent breakage thereof under the shock of being struck by the movable contact member, without impairing the electrical conductivity of the fixed contact mem-

ber. The bolt 18, besides acting as a fastener for the fixed contact, serves to electrically connect said contact with the cable 9. The protecting pipe 10 of the cable is made in sections and the ends of the sections 70 are separated at a point within the seat 8 so that a clip 32 can be applied around the cable between the adjacent ends of the pipes, the ends of the clips being apertured to fit over the threaded stud or extremity 33 of the 75 bolt. A nut 34 screws on this stud and clamps the clip against the head of the bolt, and in this manner, the clip is firmly clamped around the cable and is also clamped against the head of the bolt to make 80 a good electrical connection between the cable and the bolt. To prevent the nut 34 from turning, one extremity, 35, of the clip is bent downwardly over the nut.

The movable contact of the switch is a 85 block 36 of non-magnetic electrically conductive material which is carried by the lower extremity of a swinging arm 37 adapted to swing toward and from the fixed contact and thereby bring the contacts into and 90 out of engagement. The arm 37 is rigid with an armature 38 which is fulcrumed on a horizontal axis in the upper portion of the housing, the axis being so located and the mass of the armature being so distributed that 95 the armature will be normally held by gravity in the position shown in full lines in Fig. 1 with the contacts separated. When the magnetic circuit is closed and the armature is attracted, it will swing to the position shown in dotted lines in Fig. 1 and the contacts will be caused to engage. The armature and movable contact are preferably carried by the cover 39, so that when the latter 100 is removed, the armature and movable contact will also be removed from the body and the fixed contact will be exposed, all the working parts being thus made accessible so that the repairing or renewing of any element is facilitated. To support the armature 105 the cover is provided on its under side with depending lugs 40 spaced such a distance apart that the armature 38 can be placed between the lugs. Through these lugs are inserted pivot pins 41 which enter the 110 opposite sides of the armature and thereby support the same so that it may swing freely. One end of the armature is provided with a curved polar face 42 concentric with the axis of rotation, while the opposite 115 end is provided with a flat polar face 43 that is approximately parallel with the central radius of the curved polar face 42, this peculiar form of the armature causing it to 120 co-operate with the energizing pole pieces in such manner that a maximum magnetic pull will be exerted on the armature when the switch is closed and the contacts will be held firmly together while current flows 125 through the switch box.

The cover is formed with a depending peripheral flange 44 which fits around the outside of the housing to form a weather-tight joint and screws 45, passing downwardly through the cover and engaging threaded thimbles 46 anchored in the walls of the housing, removably secure the cover in place. The cover shown in Fig. 1 has a central contact block or plate 47 with which the collector shoe 48 of the car engages to receive current for the motor, the said contact 47 being so shaped that its top surface projects somewhat above the top surface of the cover. The end sections 49 and 50 of the cover are made of magnetizable material and formed on the bottom sides of said sections are pole pieces 51 and 52. The sections of the cover may be anchored together in any suitable manner, as by forming the middle section with tongues 53 so shaped as to constitute anchoring means with which the end sections will interlock when they are cast. The sections of the cover may be tied together by zig-zag wires 54 each arranged in a joint between two adjacent sections and embedded partially in both, as shown in Fig. 2. The pole piece 51 is triangular and has its inner end made arcuate to form a polar face 55 concentric with the axis of the armature while the pole piece 52 is in the form of a parallelogram in longitudinal section and has a horizontal bottom or polar face 56. When the magnetic circuit is open the armature will lie at an angle to the pole pieces and the maximum lines of force cannot pass through it. When the energizing magnets 56 and 57 on the car are directly above the sections 49 and 50 of the cover the pole pieces are energized and the armature attracted so that it will swing on its axis to carry the movable contact toward the fixed contact, the engagement of the contacts arresting the movement of the armature in the position shown in dotted lines in Fig. 1 in which position the magnetic circuit will be fully closed. When the circuit is closed, the lines of magnetic flux passing between the pole piece 51 and the adjacent end of the armature extend approximately at right angles to those passing between the opposite end of the armature and the pole piece 52, and as the result of this change in the direction of the flow of the magnetic lines of force, a much stronger magnetic torque is produced than has been possible in any previous construction. Said magnetic torque tends to turn the armature to a neutral position between the pole pieces. This neutral position, however, can never be attained because the engagement of the movable contact 36 with the fixed contact 47 arrests the movement of the armature as before stated. Thus there will be a strong pull on the armature while the pole pieces

are energized, and as a result, a firm, reliable engagement between the contacts will be maintained. In order to provide for an effective passage of current from the contact 36 to the contact 47, one or a pair of flexible conductors 58 are employed, the said conductors having their upper ends anchored in a threaded thimble 59 that screws into the bottom surface of the intermediate section of the cover while the lower ends of the flexible conductors are anchored in the block 36. The flexible conductors extend through a passage 60 leading from the bottom to the top of the armature. Since the conductors 58 are flexible, they do not interfere with the movement of the armature and as they are insulated by their wrapping or covering from the armature they prevent interference between the electric and magnetic circuits. As the electric contacts are both insulated and the body of the box is of concrete or cementitious material, dissipation of the current is prevented and the full strength of the current will pass to the collector shoe 48 and thence into the working circuits on the car.

In order that the engaging faces of the contacts may rest squarely against each other, the movable contact is formed with side plates 61 which pass on opposite sides of the end of the arm 37, a pivot pin 62 being inserted through said side plates and the end of said arm and being insulated from the arm as indicated at 63.

In order that the bolt 18 and the parts coacting therewith may be easily manipulated, a notch or recess 64 is formed in the outer wall of the seat 8 in alinement with the opening 65 in the end wall of the housing through which the bolt 18 and bushing 19 are inserted.

In Fig. 8, the cover 66 is made of magnetic material with the pole pieces 67 and 68 in one integral member and the central contact plate or block 69 is set into the upper surface of the cover, as clearly shown in the drawing.

While we have described what we believe to be the best embodiment of our invention, it is to be understood that such changes may be made when desired as are within the scope of the claims appended hereto.

Having thus described our invention, what we claim and desire to secure by Letters Patent is:—

1. A contact switch box including a fixed contact, a movable contact arranged to engage the fixed contact, and magnetically influenced means for operating said movable contact, said means including pole pieces and an armature, one of the pole pieces being arranged in the path of movement of one face of the armature, the remaining

10 pole piece and the armature being at all times free of contact.

15 2. A contact switch box including fixed and movable contacts, a swinging armature carrying the movable contact, and pole pieces arranged at opposite sides of the axis of the armature, one pole piece being arranged in the path of movement of one end of the armature and the opposite pole piece 20 having a face concentric with the axis of rotation of the armature.

25 3. A contact switch box comprising an element with which a collector shoe of a car is adapted to engage, a fixed contact, a movable contact arranged to engage the fixed contact, and magnetically influenced means for operating said movable contact, said means including pole-pieces and an armature, one of said pole-pieces being arranged in the path of movement of one face of the armature and the remaining pole-piece and the armature being at all times free of contact.

30 4. A contact switch box having pole pieces and a swinging armature in co-operative relation therewith, a fixed contact, a movable contact carried by the armature, a fixed element for engaging a collector shoe on a car, and a flexible conductor connected directly to said element and also directly to the movable contact whereby current is supplied to a car.

35 5. A contact switch-box comprising an element with which a collector shoe of a car is adapted to engage, an armature having a passage through it, magnetic means for moving the armature, a fixed contact, a movable contact carried by the armature to engage the fixed contact, and a flexible conductor connected directly to the movable contact, and also directly to said shoe-engaged element and passed through the passage in the armature.

40 6. A contact switch box including a casting, a removable cover therefor, an armature pivotally hung from and removable with the cover, and pole pieces arranged at opposite sides of the axis of the armature, one pole piece being arranged in the path of movement of one end of the armature and the opposite pole piece having a face concentric with the axis of rotation of the armature.

45 7. A contact switch box comprising a housing, circuit-opening and closing means therein including movable and fixed contacts, an insulating plate within the housing, a bolt passing through a wall of the housing and holding said plate against the housing and the fixed contact against said plate, a supply conductor, and a clip attaching the conductor to the bolt and cooperating with the latter to electrically connect the fixed contact with the conductor.

50 8. A contact switch box comprising a housing, a supply conductor exterior thereto, circuit opening and closing means within the housing, a metallic member extending into the housing to form an electrical connection between said means and conductor, 70 said member having a threaded outer extremity, a clip applied to the conductor and to the threaded extremity of the member, and a nut threaded on the member for holding the clip in place.

75 9. A contact switch box comprising a housing, a supply conductor exterior thereto, circuit opening and closing means within the housing, a metallic member extending into the housing to form an electrical connection between said means and conductor, 80 said member having a threaded outer extremity, a clip applied to the conductor and to the threaded extremity of the member, and a nut threaded on the member for holding the clip in place, said clip having a portion bent against the side of the nut to prevent loosening thereof.

85 10. In a contact switch box, the combination of a housing having a seat on one external wall, a conductor resting on the seat, a support for the housing, and devices applied to the conductor and fastened to the support whereby said devices and the conductor form means for securing the housing to the support.

90 11. In a contact switch box, the combination of a housing having a base extension provided with a seat, a conductor resting on the seat, a support for the housing, and 100 clips applied to the conductor and fastened to the support to hold the conductor on the seat and the housing on the support.

95 12. A contact switch box comprising a housing having a seat on the outside thereof, 105 a conductor engaging the seat, there being a notch in the outer wall of said seat, said notch extending transversely of the seat, circuit opening and closing means in the housing, and a detachable electric connection 110 between the conductor and said circuit opening and closing means, said connection terminating on the outside of the housing within the seat and in alinement with the notch in the outer wall of the latter, where- 115 by the connection is removable through said notch.

120 13. In a contact switch box, the combination of a housing having an open trough-like seat, a conductor extending through the seat and including a cable and a protecting pipe, said pipe being made in sections arranged in alinement and constituting continuations of one another and having adjacent ends separated within the seat, circuit- 125 opening and closing means in the housing, and means applied to the cable between the separated ends of the protecting pipe and

connected with the circuit opening and closing means for supplying current thereto from the cable.

14. A contact switch box comprising a housing, a fixed contact therein, a removable cover having pole pieces at its ends on its under side and an intermediate electrically conductive non-magnetic portion, an armature pivotally suspended on the under side of the non-magnetic portion of the cover between the pole pieces thereon, a movable contact carried by the armature to engage the fixed contact in the housing, said movable contact being of non-magnetic material, and an insulated conductor secured to and extending between the said movable contact and the non-magnetic portion of the cover.

15. A contact switch box comprising a housing, a fixed contact therein, a removable cover for the housing having pole pieces on its under side, an armature pivoted on the under side of the cover between said pole pieces, a non-magnetic projection on the cover, an arm projecting from the armature, a contact plate pivoted to the free end of said arm, and an insulated conductor secured to and extending between said contact plate and the non-magnetic projection.

16. A surface contact device for electric railways having a pivoted armature carrying a movable contact, pole pieces arranged at opposite sides of the axis of said armature, one of said pole pieces extending opposite one end of the armature and having a curved face presented to said end of the armature which is correspondingly formed, the other pole piece arranged in the path of the other end of said armature, and a fixed contact adapted to be engaged by said movable contact when the armature is actuated by magnetic force through said pole pieces.

17. A surface contact device for electric railways having a pivoted armature carrying a movable contact, pole pieces arranged at opposite sides of the axis of said armature, one of said pole pieces projecting beyond the axis of the armature and having a curved face presented to a correspondingly formed end of the armature, the other pole piece terminating short of the axis of the armature and arranged in the path of the other end of said armature, and a fixed contact adapted to be engaged by said movable contact when the armature is actuated by magnetic force through said pole pieces.

18. A surface contact device for electric railways having a pivoted armature carrying a movable contact, pole pieces arranged at opposite sides of the axis of said armature, one of said pole pieces extending opposite one end of the armature and having a curved face presented to said end of the armature which is correspondingly formed, the other pole piece arranged in the path

of the other end of said armature, and a fixed contact adapted to be engaged by said movable contact when the armature is actuated by magnetic force through said pole piece, and the latter capable of exerting the maximum pull on said armature when the contacts are engaged.

19. A contact switch box comprising a housing, a fixed contact therein, a removable contact having pole pieces at its ends on its under side and an intermediate electrically conductive non-magnetic portion, an armature pivotally suspended on the under side of the non-magnetic portion of the cover between the pole pieces thereon, one of said pole pieces being arranged in the path of movement of one end of the armature and the opposite pole piece having a face concentric with the axis of rotation of the armature, a movable contact carried by the armature to engage the fixed contact in the housing, said movable contact being of non-magnetic material, and an insulated conductor secured to and extending between the said movable contact and the non-magnetic portion of the cover.

20. A surface contact device for electric railways having a magnetically operated movable contact, and a fixed contact comprising a support, a carbon block carried thereby and a piece of netting interposed between said carbon block and support and providing an air space between them for cushioning the carbon.

21. A switch box including a movable contact, a fixed contact in electrical communication with a source of supply, an armature operating the movable contact, and magnetic pole pieces for operating the armature, the magnetic face of one pole piece being curved on a surface concentric with the movement of the armature, the magnetic face of the other pole piece constituting a plane surface.

22. A switch box including a movable contact, a fixed contact in electrical communication with a source of supply, an armature operating the movable contact, and magnetic pole pieces for operating the armature, the magnetic face of one pole piece being curved on a surface concentric with the movement of the armature, the magnetic face of the other pole piece constituting a plane surface arranged in the path of movement of the operating portion of the armature.

23. A switch box including a movable contact, a fixed contact in electrical communication with a source of supply, an armature operating the movable contact, and magnetic pole pieces for operating the armature, the magnetic face of one pole piece being curved on a surface concentric with the movement of the armature, the magnetic face of the other pole piece constituting a plane surface approximately perpendicular

with a line tangential to the curved face of the first mentioned pole piece.

24. A contact switch box including a fixed contact, a movable contact, an armature for operating the latter, and independent pole pieces adapted to magnetically affect the armature, one of said pole pieces having a curved magnetic face arranged beyond the path of travel of the armature and the other of said pole pieces having a flat magnetic face arranged across the path of travel of the armature, said armature having a curved face to coöperate with one of said pole pieces

and a flat face to coöperate with the remaining pole piece.

In testimony whereof we affix our signatures in the presence of two witnesses.
